WILLIAM RITCHIE, OF WILMINGTON, ILLINOIS.

Letters Patent No. 100,072, dated February 22, 1870.

IMPROVEMENT IN INSTRUMENTS FOR DRAWING GEOMETRICAL LINES.

The Schedule referred to in these Letters Patent and making part of the same.

To all whom it may concern:

Be it known that I, WILLIAM RITCHIE, of Wilmington, in the county of Will, and State of Illinois, have invented a new and improved Instrument for Drawing Geometrical Lines; and I do hereby declare that the following is a full, clear, and exact description thereof, which will enable others skilled in the art to make and use the same, reference being had to the accompanying drawings forming part of this specification, in which—

Figure 1 represents a plan or top view of my improved instrument for drawing geometrical lines, showing it adapted to the production of parallel and radial straight lines and of regular circles.

Figure 2 is a side elevation of the same.

Figure 3 is a plan or top view of the grooved trammel-bed used in connection with the same.

Figure 4 is a plan or top view of the trammel-slide and bed.

Figure 5 is an inverted plan view of the trammel-slide.

Figure 6 is a side view of the pencil-tube.

Figure 7 is a plan or top view of the same.

Figure 8 is a plan or top view of the instrument, showing it adapted to the production of spiral and eccentric curves around a fixed center.

Figure 9 is a plan or top view of the same, showing it adapted to the production of volutes around an oval, and also the ovals.

Figure 10 is a plan or top view of the center block.

Similar letters of reference indicate corresponding parts.

This invention relates to a new instrument which can be used for producing all kinds of curves as well as straight lines, and which can be readily set and adjusted to draw with exactness the requisite curve or line.

The invention consists chiefly in the arrangement of a frame which carries a pencil or other marking instrument, and which is supported on a revolving frame or bed, wherein it can also slide.

The combined sliding and revolving motion of the instrument produces the volutes, the grades of which can be regulated by the angle at which the instrument is caused to slide.

The invention also consists in the general combination of devices used on the instrument with a trammel for producing ovals and volutes around the same.

A in the drawing represents a bar made of wood or other suitable material, provided at one end with a roller, B, whose diameter is such that it holds the bar about half an inch above the level on which the roller rests.

C is an arm projecting at right angles from the bar A, near to the end on which the roller B is attached.

The outer end of the arm C is supported by a castor-wheel, D, as shown.

The bar A is slotted longitudinally, as shown, and is provided with an extension piece or slide, E, which is a bar secured by screws *a a* to the under side of the bar A, and longitudinally adjustable thereon.

To the inner end of the slide E is pivoted, by a pin, *b*, a rod or center arm, F, which works on the under side of the slide E, so that it may be swung entirely under the same, as by dotted lines in fig. 1, or at right angles thereto, as by full lines in the same figure, or at any suitable intermediate angle.

The outer end of the center arm works on a graduated arc, G, which projects from the outer end of the slide E, and to which the arm can be clamped by a suitable screw, *c*, in any desired position.

Between the inner end of the slide E and the arm C is arranged, in or on the bar A, a vertical tube, *d*, for the reception of a pencil, H. This tube may either be fitted through the bar A, as in fig. 1, or it may be secured to the side of the same by means of projecting ears *e* and screws *f*, as in figs. 6 and 7.

The pencil H should be weighted at its upper end to make the required marks without requiring additional pressure.

I represents a block of suitable length, grooved longitudinally at its upper face, and provided with one or more friction-rollers *g* at the bottom of the groove.

At one end projects from the block I an ear, *h*, which has a small aperture to receive a pin, *i*, by which the block can be pivoted to a drawing-board. At the opposite end, the block is supported by one or more rollers *j j*.

The center arm F is, after the block has been pivoted to the board, placed into the groove of the same as shown, and can readily slide therein, as the friction-roller facilitates the motion.

The block can readily revolve on the pin *i*.

If the center arm should be locked to the block, the pencil would, when the device was set in motion, describe a regular circle around the pin *i*, as no other motion of either part is then possible. As, however, the center arm fits loose into the groove of the block, and can easily slide therein, the motion produced will be entirely different, provided the center arm be clamped to the arc, in a position between the two shown in fig. 1.

The roller B will have the tendency to revolve in a straight line, while the rotation imparted to the frame forces it to revolve on the pin *i*. The two motions thus combined will produce a component movement, recorded by the pencil in form of a spiral line or volute around the circle.

The degree of the volute is varied by the angle at which the center arm is clamped.

During the motion of the instrument the arm F slides in the block, and at the same time the block revolves on the pin i.

Fig. 8 clearly shows the position of the instrument and several curves described by it.

Into the pivoted end of the block I is fitted a screw, K, which can be moved in or out, and which with its head strikes against the downward-projecting pivot b, to thereby regulate the diameter of the circle around which the volute is described.

When the screw K strikes the pivot b, the center arm can slide no further inward, and thereby the further revolution of the instrument will describe a regular circle around the pin i.

Instead of the block I and the center pin i a double grooved trammel-bed, J, carrying a trammel-slide, L, with two pins l l, may be employed, the slide having its upper surface grooved similar to the block I.

The trammel-bed is by two pins secured to the drawing-board, and the center arm fitted into the groove of the slide.

The motion of the instrument on the trammel-bed will produce ovals and volutes thereto, as indicated in fig. 9.

When the instrument is placed upon the block I, and the center arm set at right angles to the bar A, the device may be moved longitudinally in the groove of the block to produce parallel lines m m, the distances between which are regulated by the extension of the lever A on the slide E.

When the center arm is folded directly under the slide, so that the block I will also be under the slide and bar A, radial lines n n can be drawn by gradually turning the block and sliding the center arm in and out without turning the instrument.

The grooved block, being pivoted to the drawing-board, will revolve on the pivot, describing a true circle, whether there are wheels on it or not. The wheels are placed there merely to reduce friction on the drawing-board, and the wheel within the groove of the block is simply to reduce the friction that would ensue from the center arm sliding on the bed of the groove.

If the center arm of the instrument is placed in the grooved block, it forms a radius, of which the roller B is the tangent and the pivot of the grooved block is the center.

If the tangent and radius are at right angles, and the instrument is pushed forward, the center arm, being retained in position by the edges of the groove, forms a connected lever, with which the instrument revolves on the pivot, making a true circle.

If the roller B and the bar A are at right angles, and the bar A and the center arm are at right angles, the roller B and the center arm will be parallel, and being pushed, as above stated, there being now no obstruction to the center arm, the instrument will de-

scribe a straight line until the pivot of the slide comes in contact with the bed-screw of the grooved block, when it will make a circle.

If the center arm and the roller B be fixed at an angle of forty-five degrees and pushed, as above, the friction being light and the roller B being heavy, it is not effected by the friction, but pursues its path at the same angle, and causes the center arm to slide through the grooved block while revolving, and recording a true volute of forty-five degrees. The roller B does not slip, its variations being caused by simply changing the plane of its motion.

The following is the rule to obtain a volute of a given character, the diameter of the eye and the extreme outer point of the volute from the center being given, with the angle at which the curve shall deviate from a straight line:

Adjust the instrument by fastening the slide so that the distance between the center of the pivot, which fastens the center arm with the slide, and the center of the pencil-tube shall be one-half the diameter of the eye required, fasten the center arm to the graduated arc at the required angle, and place the pencil in the pencil-tube at the required distance from the center, and move the instrument, as above, until the pivots of the grooved block and center arm are perpendicular. Any outer or intermediate lines verging to the same center, are formed by simply taking another point of commencement with the pencil, without altering the adjustment of the instrument.

Where parallel lines are required, fasten the slide so that the distance between the end of it and the pencil-tube shall be the distance required between the lines. Describe the outer line first until a point is arrived at where the radial distance between it and the adjoining curve is equal to that required, then remove the pencil and shift the slide close up to the pencil-tube and describe. Any intermediate lines are formed by securing the slide to the arm of the instrument at a distance from the pencil-tube equal to the distance between the inside line and the required line.

Having thus described my invention,

I claim as new and desire to secure by Letters Patent—

1. The combination, with each other, of the bar A, roller B, pivoted center arm F, and arc G, all arranged as described, to constitute a drawing-instrument, as specified.

2. The grooved block I pivoted to the drawing-board and adapted to receive the center arm F of the drawing instrument, as set forth.

3. The combination of the grooved trammel-arm and friction-wheel with the center, each of said parts being constructed and arranged as and for the purpose specified.

WM. RITCHIE.
